(57) **ABSTRACT**

The present invention is directed to a monopole/dipole symmetric radiator structure that includes a symmetric planar radiator. When the symmetric radiator is part of an operative monopole or dipole antenna, the antenna exhibits a wide or broad bandwidth, a VSWR of less than about 3:1, a relatively constant gain perpendicular or broad-side to the plane of the radiator, and is vertically polarized. In one embodiment, the symmetric planar radiator has an outer edge that is bilaterally symmetrical. In another embodiment, the outer edge of the symmetric planar radiator is bilaterally symmetric and a closed inner edge of the radiator that defines a void is also bilaterally symmetric.

**SYMMETRIC PLANAR RADIATOR
STRUCTURE FOR USE IN A MONOPOLE OR
DIPOLE ANTENNA**

FIELD OF THE INVENTION

The present invention relates to a radiator structure that is part of a monopole or dipole radiator structure that forms an antenna.

BACKGROUND OF THE INVENTION

Generally, a monopole antenna is comprised of a radiator and a ground plane. In an ideal monopole, the radiator is disposed perpendicular to and separated from an infinite ground plane. With reference to FIGS. 1A-1C, the ideal monopole respectively exhibits a characteristic "half donut" radiation pattern 20, a characteristic two, half-circles elevational radiation pattern 22 relative to an image plane 24 (the image plane being an imaginary plane that is parallel to or coextensive with the ground plane), and a characteristic omnidirectional azimuthal radiation pattern 26 in the image plane 24. Moreover, the electrical field of the electro-magnetic wave that the antenna is capable of producing if the antenna is used to transmit a signal or capable of receiving if the antenna is used to receive a signal is vertically polarized, i.e., the electric field vector is perpendicular to the ground plane.

Generally, a dipole antenna is comprised of a pair of radiators. In an ideal dipole, the radiator structures are coplanar and separated from one another. With reference to FIGS. 2A-2C, the dipole respectively exhibits a characteristic "full donut" radiation pattern 30, characteristic two circle elevational pattern 32 relative to an image plane 34, and a characteristic omnidirectional azimuthal pattern 36 in the image plane. The electrical field of the electro-magnetic wave that the antenna is capable of producing if the antenna is used to transmit a signal or capable of receiving if the antenna is used to receive a signal is vertically polarized, i.e., the electric field vector is perpendicular to the image plane.

Two characteristics of any antenna, including monopole and dipole antennas, are the bandwidth (BW) of the antenna and the voltage standing wave ratio (VSWR) of the antenna. The bandwidth of an antenna is typically defined as the difference between the low frequency (f_{low}) and high frequency (f_{high}) at which the power output of the antenna is within 3 dB of the maximum power output of the antenna. The wavelengths associated with f_{low} and f_{high} respectively are λ_{low} and λ_{high} . The VSWR is a measure of how much energy is delivered to the antenna as opposed to how much power is reflected from the antenna. Alternatively, the VSWR is a measure of how closely the antenna impedance and the impedance of the transmitter/receiver associated with the antenna are matched. A VSWR of 1:1 indicates that there is no reflected energy or that the impedances are matched.

SUMMARY OF THE INVENTION

Presently, there are several known monopole antennas that each have a symmetric planar radiator, operate over a particular bandwidth, exhibit an acceptable VSWR over the bandwidth, are vertically polarized, and have elevational and azimuthal radiation patterns. However, these known monopole antennas each fail to exhibit a combination of: (a) at least a 3:1 bandwidth, (b) a VSWR of less than about 3:1 over the bandwidth, (c) vertical polarization, and (d) a relatively constant gain perpendicular or broad-side to the plane of the radiator.

2

With reference to FIG. 3, an elevational radiation pattern 40 for a typical planar monopole antenna shows reduced gain perpendicular to the plane of the radiator. The radiator of the monopole lies in the perpendicular plane defined by the line 5 extending from 0° to 180° and above the line extending between -90° and 90°, the ground plane lies in the perpendicular plane defined by the line extending between -90° and 90°. A comparison of the elevational radiation pattern for a typical planar monopole antenna with a planar radiator in FIG. 3 to the elevational radiation pattern for an ideal monopole antenna in FIG. 1B shows the loss in gain broadside to the plane of the radiator in the typical planar monopole antenna. This loss in gain is reflected in the lobing/nulling of the elevational radiation pattern. Lobing or nulling denotes a substantial drop of the radiation pattern at one or more elevational angles. Further, there are no known dipole antennas with planar radiators that exhibit the noted combination of characteristics.

The present invention is directed to a radiator structure comprising a symmetric planar radiator. When the symmetric radiator structure is combined with the other elements necessary to realize a monopole/dipole antenna, the resulting antenna exhibits the following operational or performance characteristics: (a) a 3:1 bandwidth, (b) a VSWR of less than about 3:1 over the bandwidth, (c) vertical polarization, and (d) a relatively constant gain perpendicular or broad-side to the plane of the radiator with any dropouts over frequency less than 6 dB.

A planar radiator is deemed to be symmetric based on an analysis that involves:

(a) defining a pseudo-ground plane and a normal plane that is perpendicular to the pseudo-ground plane, (b) positioning the planar radiator so as to be perpendicular to both the 35 pseudo-ground plane and the normal plane, (c) positioning the planar radiator so that a pseudo-contact portion of the edge of the radiator contacts the pseudo-ground plane, the pseudo-contact portion is the portion of the edge of the planar radiator that would be closest to an infinite ground plane if the 40 radiator were used to form a monopole antenna with an infinite ground plane, (d) positioning the planar radiator so that the normal plane passes through the mid-point of the pseudo-contact portion when the pseudo-contact portion is a straight portion of the edge or defined by a number of separated points or a combination of one or more points and one or more straight sections that are separated from one another, or through the single point that defines a pseudo-contact portion; (e) positioning the planar radiator such that the radiator is oriented to the pseudo-ground plane as the radiator would be oriented to an infinite ground plane if the radiator were used to form a monopole with an infinite ground plane. A planar radiator that is positioned relative to a pseudo-ground plane and a normal ground in this manner is considered to be symmetrical if the planar radiator is bilaterally symmetrical relative to the normal plane. The planar radiator, in addition to being symmetric, has a symmetric shape that is fundamentally responsible for producing the noted bandwidth, VSWR, vertical polarization, and the relatively constant gain broad-side to the plane of the planar radiator when the planar radiator is operational in a monopole or dipole antenna.

The symmetry of a planar radiator can be attributable to the outer edge of the radiator, a closed inner edge of the radiator that defines a void, or both an outer edge and a closed inner edge. A void is an area that is enclosed by a closed inner edge. 55 There are numerous symmetric shapes for a planar radiator in which the outer edge is symmetric or both the outer edge and each closed inner edge are symmetric and, when combined

with the other elements needed to form a monopole/dipole antenna, result in an antenna with the noted operational performance.

Characteristics of at least a subset of the numerous planar radiators with symmetric outer edges that when combined with the other element(s) needed to form a monopole or dipole antenna provide the noted operational performance have been identified. Before describing these characteristics, it should be appreciated that many of the symmetric shapes that have these characteristics are superficially similar in shape to many of the currently known symmetric planar radiators that do not result in a monopole/dipole antenna with the noted operational performance. Consequently, in some cases, the differences in shape may not appear significant but the difference in performance is substantial. The characteristics of numerous planar radiators with symmetric outer edges that when combined with the other element(s) to form a monopole/dipole antenna with the noted operational performance are that the symmetric shape has: (a) a width profile that has at least one wide-narrow-wide transition and (b) at least one wide-narrow-wide transition in the width profile has particular dimensional characteristics.

The concept of a width profile can be understood with respect to a relatively straight-forward example involving a planar radiator defined by an outer edge and no closed inner edge (i.e., the radiator does not enclose a void). If there is no horizontal line parallel to the pseudo-ground plane that can be drawn through the planar radiator that passes through a gap between two portions of the radiator, a width profile is the plotting of the horizontal width (on a vertical axis) versus the vertical location relative to the pseudo-ground plane beginning at the point or points on the outer edge that is/are farthest from the pseudo ground plane and proceeding to the pseudo contact portion (on a horizontal axis) or vice-versa. If the width profile yields at least one local minimum located in between two local maximums, the radiator has a wide-narrow-wide transition in the width profile.

The dimensional characteristics are: (a) a vertical distance between a local minimum and the vertically closest of the local maximum on one side of the local minimum and the local maximum on the other side of the local minimum and (b) a horizontal distance between a local minimum and the horizontally closest of the local maximum on one side of the local minimum and the local maximum on the other side of the local minimum. If the vertical distance associated with at least one local minimum is at least 0.02 of the wavelength associated with the frequency that defines the low end of the bandwidth (λ_{low}) and the horizontal distance associated with the local minimum is at least $0.01\lambda_{low}$, the radiator satisfies the dimensional requirement. A planar radiator that satisfies the wide-narrow-wide and dimensional requirements is sufficient to realize the noted benefits.

There are numerous planar radiators with symmetric shapes that, when combined with the other element(s) needed to form a monopole or dipole antenna, result in an antenna with the noted performance but that do not have the wide-narrow-wide and dimensional characteristics. However, it has been determined that a modification to a raw or unmodified width profile associated with some of these symmetric shapes will produce a modified width profile that has the characteristics of an symmetric radiator that will function in the desired manner. In other words, the modified profile reflects the reality that planar radiators with these symmetric shapes will function as desired. The modification recognizes that certain features of some these symmetric shapes causes the shape to fail to have one or more of the required characteristics. Among these features are: (a) an outer edge with at least one small

amplitude ripple that causes the radiator to not satisfy the vertical dimension characteristic, (b) an outer edge with at least one ripple and surrounding structure that causes the radiator to not satisfy the horizontal dimension characteristic, 5 and (c) an outer edge with at least one right angle bend. In the case of a small amplitude ripple, the vertical distance between each local minimum that correlates to the ripple and the vertically nearest local maximum of the two local maximums that bracket each such local minimum may be insufficient, but 10 the vertical distance between the same local minimum and a different local maximum does satisfy the requirement. In the case of a ripple and surrounding structure that cause the radiator to not satisfy the horizontal dimension characteristic, the horizontal distance between each local minimum and the horizontally nearest local maximum of the two local maximums that bracket the local minimum may be insufficient, but 15 the horizontal distance between the same local minimum and a different local maximum may satisfy the requirement. With respect to both of these ripple structures, the ripple essentially 20 does not have a significant adverse effect on whether the symmetric shape facilitates the noted performance in a monopole/dipole antenna but does cause the symmetric shape to fail to have one of the characteristics. In the case of an outer edge with at least one right angle bend, such bends can result 25 in a width profile with horizontal and/or vertical sections that can make it impossible to determine the location of a local maximum or local minimum. A common characteristic of symmetric shapes that have one or a combination of these characteristics is that each of these characteristics presents, 30 from a Fourier analysis perspective, high frequency components in the unmodified width profile. If the unmodified width profile is analyzed to determine the first harmonic and then the unmodified width profile is filtered so as to pass substantially only the first harmonic identified by the Fourier analysis, a modified width profile is produced that exhibits the 35 wide-narrow-wide and dimensional characteristics. The filtering produces a modified width profile that reflects the “essence” of the symmetric shape. It should be appreciated that a symmetric shape with a width profile that does not 40 exhibit one of the characteristics due only to the presence of right angle bends in the outer edge can be filtered in a different fashion. For example, the mid-points of horizontal sections can be defined as local minimums or local maximums.

The width profile that is ultimately assessed to determine 45 whether the wide-narrow-wide and dimensional characteristics are present is occasionally referred to herein as the assessment width profile and can be the original width profile for a symmetric radiator or a modified width profile that reflects a modification to the outer edge of the radiator and/or some 50 kind of processing of the original width profile to produce a modified width profile.

There is another group of symmetric shapes that, when combined with the other element(s) needed to form a monopole or dipole antenna, result in an antenna with the noted 55 performance but that do not have the wide-narrow-wide and dimensional characteristics. Characteristic of this group of symmetric shapes is at least one pair of downwardly extending protuberances, sometimes referred to as “stalactites”. When such a protuberance is present, a horizontal line can be 60 drawn that extends through a gap between the protuberance and another portion of the radiator. Further, there is a local inflection point in the planar radiator located above the portion of the horizontal line extending through the gap. A local inflection point is a point on the outer edge that has a zero 65 slope. Further, the portion of the outer edge immediately to one side of the point has a positive slope, the portion of the outer edge immediately to the other side has a negative slope,

and there is a portion of the radiator that is located immediately above the inflection point. The presence of the gap forecloses the possibility of producing a width profile for the planar radiator and, because a width profile cannot be produced, determining whether the radiator has the characteristics of a symmetric radiator that, when combined with the other element(s) needed to form a monopole or dipole antenna, produces the noted operational performance. To address this issue, the outer edge of the planar radiator is redefined. The redefined outer edge is then used to produce a modified width profile relative to the width profile before the outer edge was redefined. The modified width profile satisfies the characteristics of a symmetric radiator that will have the noted performance characteristics. In other words, the modified width profile reflects the reality that planar radiators with these symmetric shapes that have a pair of downwardly extending protuberances will function as desired. The redefined outer edge is produced by drawing a horizontal line through the local minimum associated with each of the protuberances. The portion of the horizontal line that spans a gap to either side of the local minimum replaces the portion of the outer edge of the planar radiator that extends between the local minimum and the point/points at which the portion of the horizontal line spans the gap/gaps. In the case of several protuberances being present in the symmetrical shape and two or more horizontal lines crossing a specific gap, the portion of the horizontal line closest to the pseudo-ground plane prevails in the redefined outer edge.

There is yet another group of symmetric shapes that, when combined with the other element(s) needed to form a monopole or dipole antenna, result in an antenna with the noted performance but that do not have the wide-narrow-wide and dimensional characteristics. Characteristic of this group of symmetric shapes are at least two upwardly extending protuberances, sometimes referred to as "stalagmites." When such protuberances are present, a horizontal line can be drawn that extends through a gap between at least two of the protuberances. Further, there is a local minimum in the outer edge of the planar radiator located below the portion of the horizontal line extending through the gap. The presence of the gap forecloses the possibility of producing a width profile for the planar radiator and, because a width profile cannot be produced, determining whether the radiator has the characteristics of a symmetric radiator that, when combined with the other element(s) needed to form a monopole or dipole antenna, result in an antenna with the noted operational performance. This type of gap also reflects that there functionally are at least two radiator elements present in the single planar radiator. Further, since a monopole/dipole antenna with this type of planar radiator exhibits the noted operational performance, at least one of the radiator elements satisfies the characteristics needed of a symmetric radiator that will provide the noted performance characteristics in an operational situation. Each radiator element is defined by "horizontal shading" that begins at a local maximum in the planar radiator and extends to the pseudo-contact point. Horizontal shading can be conceptualized as defining an area (in this case, the area of an element) by drawing a series of horizontal lines beginning at the local maximum and moving downward towards the pseudo-contact point with the requirement that no horizontal line can cross a gap. The areas of the elements identified in this manner will have overlapping portions because the area associated with each element must terminate at the pseudo-contact point. Each of the identified radiator elements is then used to produce a width profile. The width profile for at least one of these elements has the characteristic of a symmetric radiator that will operationally have the noted

performance characteristics. In other words, the modification reflects that certain symmetric radiators with two or more upwardly extending protuberances operationally provide the noted performance characteristics.

5 There is yet another group of symmetric shapes that, when combined with the other element(s) needed to form a monopole or dipole antenna, result in an antenna with the noted performance but that do not have the wide-narrow-wide and dimensional characteristics. This group of symmetric shapes 10 has a combination of features that make problematic the assessment of whether the characteristics needed for the noted operational performance are present.

One of these symmetric shapes has at least one pair of downwardly extending protuberances and at least a portion of 15 the outer edge has a characteristic that requires filtering (e.g., a small amplitude ripple). In this case, the outer edge is redefined to eliminate the downwardly extending protuberances, a modified width profile is produced for the symmetric shape with the redefined outer edge, and a modified-modified 20 width profile is produced by filtering the modified width profile. The modified-modified width profile reflects that the symmetric shape has the characteristics needed to operationally have the required performance.

Another one of these symmetric shapes has at least one pair 25 of downwardly extending protuberances and at least two upwardly extending protuberances. In this case, the outer edge is redefined to eliminate the downwardly extending protuberances, the radiator elements are identified with horizontal shading, and modified width profiles are produced for 30 each of the radiator elements. At least one of the modified width profiles reflects that the symmetric shape has the characteristics needed to operationally have the required performance. The width profiles for the elements are referred to as modified width profiles because neither of these profiles is a 35 width profile for the actual symmetric shape of the radiator.

Yet another of the symmetric shapes has at least one pair of downwardly extending protuberances, at least two upwardly extending protuberances, and at least a portion of the outer edge has a characteristic that requires filtering. In this case, 40 the outer edge is redefined to eliminate the downwardly extending protuberances, the radiator elements are identified with horizontal shading, a modified width profile is produced for each of the identified elements, and a modified-modified width profile is produced for each of the elements that has a 45 shape for which filtering of the width profile is appropriate. At least one of any of the modified and modified-modified width profiles reflects that the symmetric shape has the characteristics needed to operationally have the required performance.

An additional one of these symmetric shapes has at least 50 two upwardly extending protuberances and at least a portion of the outer edge has a characteristic that requires filtering. In this case, the radiator elements are identified by horizontal shading, a modified width profile is produced for each of the elements, and a modified-modified width profile is produced 55 for each of the elements that has a shape for which filtering of the width profile is appropriate. At least one of any of the modified and modified-modified width profiles reflects that the symmetric shape has the characteristics needed to operationally have the required performance.

60 A symmetric planar radiator that facilitates the noted performance in a monopole/dipole antenna can also be achieved with a planar radiator having a symmetric outer edge and a symmetric void in the radiator. A void is defined by a closed, inner edge. As such, the radiator completely surrounds the void. Further, both the outer edge and the inner edge are each symmetric. The assessment of whether a symmetric radiator with symmetric void is sufficient for realizing the noted per-

formance is done by producing a width profile in which the presence of the void is not ignored. In this case, the width at a vertical location at which a horizontal line passes through the void is the sum of the “sub-widths” of the portions of the radiator present on each side of the void. The width profile is assessed to determine whether the noted wide-narrow-wide and dimensional characteristics are present.

BRIEF DESCRIPTION OF THE DRAWINGS

FIGS. 1A-1C respectively illustrate the “half donut” radiation pattern, elevational radiation pattern, and azimuthal radiation pattern associated with an ideal monopole antenna;

FIGS. 2A-2C respectively illustrate the “full donut” radiation pattern, elevational radiation pattern, and azimuthal radiation pattern associated with an ideal dipole antenna;

FIG. 3 is an example of an elevational radiation pattern for a known planar monopole antenna that illustrates reduced gain perpendicular to the plane of the radiator, the reduced gain is reflected in the lobing/nulling present in the pattern;

FIG. 4A illustrates a planar radiator positioned relative to a pseudo-ground plane and a normal plane in a manner that allows a determination of whether the radiator is symmetric;

FIG. 4B illustrates the width profile for the symmetrical planar radiator illustrated in FIG. 4A;

FIGS. 5A-5C respectively illustrate a symmetric planar radiator with an outer edge that has a pair of small amplitude ripples that causes the radiator to not have a vertical dimensional characteristic, a width profile for the radiator, and a modified width profile;

FIGS. 6A-6C respectively illustrate a symmetric planar radiator with an outer edge with a pair of large amplitude ripples and narrow slots that separate the ripple from adjacent portions of the radiator that causes the radiator to not have a horizontal dimensional characteristic, a width profile for the radiator, and a modified width profile;

FIGS. 7A-7C respectively illustrate a symmetric planar radiator with an outer edge that has two pairs of right angle bends that render difficult the assessment of whether the radiator has a dimension characteristic, a width profile for the radiator, and a modified width profile;

FIGS. 8A-8C respectively illustrate a symmetric planar radiator with an outer edge that has a pair of “stalactites” that makes the assessment of whether the radiator has a wide-narrow-wide characteristic difficult, a modified symmetric planar radiator that has a modified outer edge relative to the unmodified symmetric planar radiator, and a modified width profile;

FIG. 9A illustrates a symmetric planar radiator with an outer edge that has three “stalagmites” that makes problematic the assessment of whether the radiator has a wide-narrow-wide characteristic;

FIGS. 9B-9D respectively illustrate a first planar element, a second planar element, and a third planar element of the symmetric radiator shown in FIG. 9A;

FIGS. 9E-9G respectively illustrate the width profile for the first radiator element shown in FIG. 9B, the width profile for the second radiator element shown in FIG. 9C, and the width profile for the third radiator element shown in FIG. 9D;

FIG. 10 illustrates a symmetric planar radiator with an outer edge with a shape that requires redefining the boundary to address multiple downward protuberances, identifying radiation elements, and filtering the width profile associated with at least one of the radiation elements;

FIG. 11 illustrates a symmetric planar radiator with a symmetrical outer edge and a symmetrical inner edge that defines a void;

FIG. 12 illustrates a monopole antenna that employs a single symmetric planar radiator;

FIG. 13 illustrates a dipole antenna that employs two symmetric planar radiators;

FIGS. 14A and 14B respectively illustrate a reference symmetric planar radiator that does not achieve the desired operational performance and an improved symmetric planar radiator that does achieve the desired operational performance;

FIGS. 15A and 15B respectively show the VSWR and the swept gain over frequency for the direction perpendicular to the plane of the radiator for the reference and improved symmetric planar radiators shown in FIGS. 14A and 14B; and

FIGS. 16A-16L show elevation plane patterns perpendicular to the plane of the radiator for frequencies covering the operating band.

DETAILED DESCRIPTION

Generally, the invention is directed to a symmetrical planar radiator for use in a monopole/dipole antenna that performs so as to have: (a) at least a 3:1 bandwidth, (b) a VSWR of less than about 3:1 over the bandwidth, (c) vertical polarization, and (d) a relatively constant gain perpendicular or broad-side to the plane of the radiator with any dropouts over frequency less than 6 dB. This operational performance for such monopole/dipole antennas is substantially attributable to the symmetric radiator.

It has been determined that there are numerous symmetrical shapes for a planar radiator in a monopole/dipole antenna that result in the antenna having the noted performance. Further, the characteristics of such symmetric planar radiators have been identified. One of the characteristics of a planar radiator for an antenna that will have the noted performance is that the planar radiator is symmetrical. With reference to FIG. 4A, this characteristic is discussed with respect to an exemplary planar radiator 50. Whether radiator 50 is symmetric is determined relative to a pseudo-ground plane 52 and a normal plane 54 that is perpendicular to the pseudo-ground plane 52. The pseudo-ground plane 52 is a plane that is located parallel to where an ideal ground plane would be located if the radiator 50 were used in a monopole antenna having an ideal ground plane. As such the pseudo-ground is not a real ground plane. The pseudo-ground is simply a reference plane that facilitates a determination of symmetry. The radiator 50 includes an outer edge 58 that defines the overall shape of the radiator 50. The outer edge 58 includes a pseudo-contact portion 60 that contacts the pseudo-ground plane 52 and is the portion of the radiator 50 that would be closest to an ideal ground plane if the radiator were used in a monopole antenna with an ideal ground plane. The pseudo-contact portion 60 of the radiator 50 is illustrated as extending along a straight line. It should be appreciated that a pseudo-contact portion 60 is not limited to a straight line but can be a single point, a number of separated points, or a combination of one or more points and one or more straight sections that are separated from one another. The radiator 50 is positioned such that the mid-point of the pseudo-contact portion 60 is intersected by the normal plane 54. If the pseudo-contact portion is a point, the mid-point of the pseudo-contact portion is the point. If the pseudo-contact portion is comprised of a number of separated points or a combination of one or more points and one or more straight sections that are separated from one another, the mid-point is the point that is mid-way between the two most separated points of the pseudo-contact portion. The radiator 50 is also positioned such that the entire radiator, other than the pseudo-contact portion 60, is entirely located to one side of the pseudo-ground plane 52. Additionally, the radiator 50 is

oriented to the pseudo-ground plane **52** as the radiator **50** would be oriented, if used in a monopole antenna, relative to an ideal ground plane. With the planar radiator **50** positioned relative to the pseudo-ground plane **52** and normal ground plane **54** in this manner, the symmetry of the radiator **50** is judged by whether the radiator is bilaterally symmetrical relative to the normal plane **54**. The planar radiator **50** is bilaterally symmetric relative to the normal plane **54**. Consequently, the planar radiator **50** is a symmetric planar radiator.

Numerous monopole/dipole antennas that employ a symmetric planar radiator exhibit the noted operational performance. An additional group of characteristics of the symmetric planar radiators employed in monopole/dipole antennas that exhibit the noted performance has been identified. These characteristics are: (a) a width profile that has at least one wide-narrow-wide transition and (b) at least one wide-narrow-wide transition in the width profile has particular dimensional characteristics. A width profile is a graph of the horizontal width of the radiator from the point(s) of the radiator that are most distant from the pseudo-ground plane to the pseudo-contact portion or visa-versa. Width is on the vertical axis of the graph and vertical position is on the horizontal axis with the zero location on the horizontal axis corresponding to the point of the radiator that is most distant from the pseudo-ground plane. It should be appreciated that the graph could be done with the zero location on the horizontal axis corresponding to the pseudo-contact portion. The width profile is described from the perspective of moving from the zero location on the horizontal axis towards the location on the horizontal axis that corresponds to the pseudo-contact portion.

A wide-narrow-wide transition is expressed in the graph by a local minimum situated between two local maximums. A profile local minimum has a zero slope with the immediately preceding portion of the graph having a negative slope (i.e., the portion towards the zero location on the horizontal axis) and the immediately following portion of the graph having a positive slope. A profile local maximum has a zero slope. The portion of a graph that immediately precedes a profile local maximum that is not associated with either of the point(s) of the planar radiator that is/are most distant from the pseudo-ground plane or the pseudo-contact portion has a positive slope (i.e., the portion towards the zero location on the horizontal axis) and the portion of the graph that immediately follows the profile local maximum has a negative slope. If a profile local maximum is associated with the point of the planar radiator that is most distant from the pseudo-contact plane, the profile local maximum has a zero slope and the portion of the graph immediately following the profile local maximum has a negative slope. If a profile local maximum is associated with the pseudo-contact portion, the profile local maximum has a zero slope and the portion of the graph immediately preceding the profile local maximum has a positive slope.

With reference to FIGS. 4A and 4B, the wide-narrow-wide characteristic is described with respect to the exemplary, symmetric planar radiator **50**. The outer edge **58** of the radiator **50** includes a member local maximum **64**, transition points **66A-66C** located between the member local maximum **64** and the pseudo-contact portion **60**, and transition points **66A'-66C'**. A member local maximum is a point or a horizontal extending line on the outer edge where the portions of the outer edge immediately to each side of the member local maximum extend towards the pseudo-ground plane. With respect to radiator **50**, the member local maximum **64** is also the point most distant from the pseudo-ground plane **52**. As such, the member local maximum **64** defines point **68**, the point on the line defined by the intersection of the normal

plane **54** and symmetric planar radiator **50** that will correspond to the zero point on the horizontal axis of the width profile.

With reference to FIG. 4B, a width profile **72** for the radiator **50** is illustrated. The width profile has points **74A-74D** that respectively correspond to the horizontal widths of the radiator **50** associated with member local maximum **64** and points **66A/66A'**, points **66B/66B'**, points **66C/66C'**, and pseudo-contact portion **60** of the radiator **50**. The width profile **72** reveals a wide-narrow-wide transition defined by the profile local minimum **74B** located between the two profile local maximums **74A** and **74C**.

The particular dimensional characteristics are: (a) a vertical distance between a profile local minimum and the vertically closest of the profile local maximum immediately to one side of the profile local minimum and the profile local maximum immediately to the other side of the local minimum and (b) a horizontal distance between a profile local minimum and the horizontally closest of the profile local maximum immediately to one side of the local minimum and the profile local maximum immediately to the other side of the profile local minimum. If the vertical distance associated with at least one profile local minimum is at least 0.02 of the wavelength associated with the frequency that defines the low end of the bandwidth (λ_{low}) and the horizontal distance associated with the same profile local minimum is at least $0.01\lambda_{low}$, the radiator satisfies the dimensional requirement. A planar radiator that satisfies the wide-narrow-wide and dimensional requirements is sufficient to realize the noted benefits.

With reference to FIG. 4B, the width profile **72** for the radiator **50** shows the profile local maximum **74C** to be vertically closer to the profile local minimum **74B** than the profile local maximum **74A**. The vertical distance between the profile local minimum **74B** and the profile local maximum **74C** is represented by distance **76** along the vertical axis of the graph of the width profile **72**. The width profile **72** for the radiator **50** also shows the profile local maximum **74C** to be horizontally closer to the profile local minimum **74B** than the profile local maximum **74A**. The horizontal distance between the profile local minimum **74B** and the profile local maximum **74C** is represented by distance **78** along the horizontal axis of the graph of the width profile **72**. If the vertical and horizontal distances associated with the profile local minimum **74B** respectively are at least $0.02\lambda_{low}$ and $0.01\lambda_{low}$, the radiator **50** satisfies the dimensional characteristics.

There are numerous planar radiators with symmetric shapes that, when combined with the other element(s) needed to form a monopole or dipole antenna, result in an antenna with the noted performance but that do not have the wide-narrow-wide and dimensional characteristics. However, it has been determined that a modification to a raw or unmodified width profile associated with some of these symmetric shapes will produce a modified width profile that has the characteristics of an symmetric radiator that will function in the desired manner. In other words, the modified profile reflects the reality that planar radiators with these symmetric shapes will function as desired. The modification recognizes that certain features of some these symmetric shapes cause the shape to fail to have one or more the required characteristics.

Among these features is an outer edge of a symmetric planar radiator with at least one small amplitude ripple. The presence of the small amplitude ripple results in the radiator not having the characteristic vertical dimension. To elaborate, if the only profile local minimums associated with the width profile of an symmetric planar radiator are associated with a ripple and the ripple has a small amplitude, the vertical distance between any such profile local minimums and the ver-

tically nearest profile local maximum of the two profile local maximums that bracket the local minimum may be insufficient. With reference to FIGS. 5A-5C, an example of such a symmetric planar radiator 80 is discussed. The planar radiator 80 is positioned such that: (a) the radiator 80 is perpendicular to a pseudo-ground plane 82 and a normal plane 84, (b) a pseudo-contact portion 86 of the radiator 80 contacts the pseudo ground plane 82; (c) the normal plane 84 passes through the midpoint of the pseudo-contact portion 86 (a single point in this example); (d) the radiator 80, other than the pseudo-contact portion 86 is located entirely to one side of pseudo-ground plane 82, and (e) the radiator 80 is oriented relative to the pseudo-ground plane as the radiator would be oriented, in a monopole antenna, to an idealized infinite ground plane. The radiator 80 is bilaterally symmetrical relative to the normal plane 84. Further, two portions of the outer edge of the radiator respectively exhibit low amplitude ripples 88, 88'.

With reference to FIG. 5B, the planar radiator 80 has a width profile 90. The width profile has two profile local minimums 92A-92B and two profile local maximums 94A-94B and a third profile local maximum 94C. At least the two profile local minimums 92A-92B and the profile local maximums 94A can be correlated to the ripple 88. With respect to the horizontal dimension characteristic and for purposes of illustration, both the profile local minimum 92A and the profile local minimum 92B satisfy the characteristic. With respect to the vertical dimension characteristic, the vertically closest of the profile local maximums to each of the profile local minimums 92A-92B is the profile local maximum 94A. The vertical distance associated with each of the profile local minimums is less than $0.02\lambda_{low}$. As such, the radiator does not possess the vertical dimensional characteristic associated with symmetric planar radiators that have the noted operational performance. However, the radiator does have the noted operational performance. It has been discovered that a low-amplitude ripple in a width profile that corresponds to a ripple in the outer edge of the radiator has, from a Fourier analysis perspective, high frequency components. Further, it has been discovered that by performing a Fourier analysis of a width profile, these high frequency components can be identified and the width profile filtered to eliminate these high frequency components and thereby produce a modified width profile that reflects the "essence" of the shape of the radiator that facilitates the operational performance of the radiator in an antenna. More specifically, the Fourier analysis of a width profile is performed to identify the first harmonic of the Fourier frequency spectrum for the profile. The width profile is then filtered so as to pass substantially only the first harmonic and thereby produce a modified width profile in which the low amplitude ripple has been substantially eliminated, thereby allowing a new profile local minimum to be assessed for the noted horizontal and vertical dimensional characteristics. With respect to the width profile 90, this modification produces a modified width profile 96 (FIG. 5C) having a profile local minimum 98 and profile local maximums 100, 102. The profile local minimum 98 now satisfies both the horizontal and vertical dimensional characteristics of a radiator that, when in operation, facilitates the noted performance. The profile local minimum 98 and profile local maximums 100, 102 satisfy the wide-narrow-wide characteristic for a radiator that facilitates the noted performance.

Also among the features that cause a symmetrical shape to fail to have one or more of the required characteristics is an outer edge of an symmetric planar radiator with at least one ripple and surrounding structure that cause the radiator to lack the horizontal dimension characteristic. To demonstrate this

type of ripple and surrounding structure, the ripple is assumed to have a relatively large amplitude that results in the vertical dimensional characteristic being satisfied for the local minimums located immediately adjacent to the ripple. The ripple is also narrow and bracketed by portions of the radiator that are separated from the ripple by relatively narrow slots. This type of structure produces a width profile with profile local minimums that satisfy the vertical dimension characteristic. However, due to the horizontal closeness of each of the profile local minimums to a profile local maximum, the radiator does not satisfy the horizontal dimensional characteristic. With reference to FIGS. 6A-6C, an example of such a symmetric planar radiator 104 with such a feature is discussed. In this regard, the planar radiator has an outer edge with ripples 112, 112'. The ripple 112 is separated by narrow slots 113A, 113B from surrounding portions of the radiator. Similarly, the ripple 112' is separated by narrow slots 113A', 113B' from surrounding portions of the radiator. The planar radiator 104 is positioned relative to a pseudo-ground plane 106 and a normal plane 108 so as to be able to assess whether the radiator 104 is symmetric. In this regard, a pseudo-contact portion 110 of the radiator 104 is positioned to contact the pseudo-ground plane 106. As can be appreciated, the radiator 104 is bilaterally symmetric relative to the normal plane 108 and, hence, considered to have the symmetric characteristic. With reference to FIG. 6B, the planar radiator 104 has a width profile 114. Associated with the width profile 114 are profile local minimums 116A, 116B and local profile local maximums 118A, 118B, and 118C. Associated with each of the profile local minimums 116A, 116B is a vertical dimension that is at least $0.02\lambda_{low}$. As such, the only two profile local minimums in the width profile 114, profile local minimums 116A, 116B, each satisfy the vertical dimension characteristic. However, neither of the profile local minimums 116A, 116B satisfies the horizontal dimensional characteristic, i.e., neither of the profile local minimums is separated from the horizontally nearest profile local maximum by at least $0.01\lambda_{low}$. However, the radiator 104 does have the noted operational performance. The Fourier based filtering addresses this issue. In the case of the width profile 114, the Fourier based filtering results in a modified width profile 120, as shown in FIG. 6C. The modified width profile 120 has a single profile local minimum 122 and profile local maximums 124, 126. Using the profile local minimum 122 and the profile local maximum 124, the horizontal dimensional characteristics is satisfied and the vertical dimensional characteristic remains satisfied. The profile local minimum 122 and profile local maximums 124, 126 satisfy the wide-narrow-wide characteristic for a radiator that facilitates the noted performance.

Also among these features that cause a symmetrical shape to fail to have one or more of the required characteristics is an outer edge of symmetric planar radiator with at least one right angle corner that makes the determination of the location of a profile local maximum or profile local minimum impossible and, as such, assessment of dimensional characteristics impossible. With reference to FIGS. 7A-7C, an example of such an symmetric planar radiator 128 with four such features is discussed. In this regard, the planar radiator has an outer edge with first and second ninety-degree corners 135A, 135B and third and fourth ninety-degree corners 135A', 135B'. The planar radiator 128 is positioned relative to a pseudo-ground plane 130 and a normal plane 132 so as to be able to assess whether the radiator 128 is symmetric. In this regard, a pseudo-contact portion 134 of the radiator 128 is positioned to contact the pseudo-ground plane 130. As can be appreciated, the radiator 128 is bilaterally symmetric relative to the normal plane 132 and, hence, considered to have the symmet-

ric characteristic. With reference to FIG. 7B, the planar radiator 128 has a width profile 136. Associated with the width profile 136 is an “indeterminate” profile local minimum that is somewhere in the area 138 and local profile local maximum 140. The indeterminate local minimum in area 138 allows a determination of whether the vertical dimension characteristic is satisfied. For purposes of illustration, it is assumed that the vertical dimension characteristic is present. However, the indeterminate local minimum does not sufficiently identify a particular point that can be used to assess whether the horizontal dimension characteristic is present in the radiator. The Fourier based filtering addresses this issue. In the case of the width profile 136, the Fourier based filtering results in a modified width profile 142, as shown in FIG. 7C. The modified width profile 142 has a single profile local minimum 144 and profile local maximums 146, 148. Using the profile local minimum 144 and the profile local maximum 146, the horizontal dimensional characteristic is satisfied and the vertical dimensional characteristic remains satisfied. The profile local minimum 144 and profile local maximums 146, 148 satisfy the wide-narrow-wide characteristic for a radiator that facilitates the noted performance.

It should be appreciated that there potentially are other features and/or combinations of features associated with outer edge of a symmetric radiator that provides the operational performance but that causes the radiator to fail to have a dimensional characteristic and/or make difficult the identification of a profile local maximum or profile local minimum that can be addressed by Fourier filtering or some other type of filtering.

There is a group of symmetric planar radiators with shapes that, when combined with the other element(s) needed to form a monopole or dipole antenna, result in an antenna with the noted performance but render assessment of whether the radiator shape satisfies the wide-narrow-wide characteristic problematic. The feature common to this group of symmetric radiator shapes is a downwardly (towards the pseudo-ground plane) extending protuberance. Characteristic of such a protuberance is that a horizontal line (i.e., a line parallel to the pseudo-ground plane) can be drawn that passes through a first portion of the radiator, a second portion of the radiator, and a gap between the first and second portions of the radiator. Further, there is a local minimum in the outer edge that is associated with the protuberance. This local minimum is sometimes referred to as a member local minimum to distinguish this local minimum from a profile local minimum in a width profile. The member local minimum has a zero slope, space below and immediately adjacent to the minimum, a portion of the radiator located above the minimum, and the outer edge extends upward (away from the pseudo-ground plane) to both sides of the minimum. Also characteristic of the downwardly extending protuberance is a member inflection point located above the horizontal line. A member inflection point has zero slope, space below and immediately adjacent to the inflection point, a portion of the radiator located above the inflection point, and the outer edge extends downwardly (towards the pseudo-ground plane) on both sides of the inflection point.

The problem in assessing the wide-narrow-wide characteristic in symmetric planar radiators that have a downwardly extending protuberance is addressed by redefining the outer edge of the radiator. More specifically, the outer edge is redefined by extending a horizontal line through the member local minimum associated with the protuberance. The horizontal line will intersect the outer edge of the radiator at one or more locations to one side of the member local minimum and potentially at one or more locations to the other side of the

member. The outer edge is redefined such that, in moving in one direction from the member local minimum, the portion of the horizontal line extending from the member local minimum to the intersection point on the outer edge that is closest (as measured along the outer edge) to the member local minimum replaces the existing outer edge between the member local minimum and the intersection point. If the horizontal line (moving in the other direction) also intersects the outer edge, the outer edge is further redefined such that the portion of the horizontal line extending from the member local minimum to the closest intersection point (as measured along the outer edge) replaces the current portion of the outer edge extending between these two points.

With reference to FIGS. 8A-8C, an example of a symmetric planar radiator with a downwardly extending protuberance, radiator 150, is discussed. The planar radiator 150 is positioned relative to a pseudo-ground plane 152 and a normal plane 154 so as to be able to assess whether the radiator 150 is symmetric. In this regard, a pseudo-contact portion 156 of the radiator 150 is positioned to contact the pseudo-ground plane 152. As can be appreciated, the radiator 150 is bilaterally symmetric relative to the normal plane 154 and, hence, considered to have the symmetric characteristic. A horizontal line 157 can be drawn through the radiator 150 such that the horizontal line passes through first and second portions of the radiator and a gap 158 between the first and second portions. As such, the radiator 150 has a downwardly extending protuberance and, due to the bilateral symmetry, a second downwardly extending protuberance. Associated with the downwardly extending protuberances are member local minimums 160, 160'. Further, there are member inflection points 161, 161' located on the portion of the outer edge located above the horizontal line. With reference to FIG. 8B, due to the presence of the downwardly extending protuberances, the outer edge of the radiator 150 is redefined. More specifically, the outer edge is redefined by respectively drawing horizontal lines 164, 164' through the member local minimums 160, 160' of the protuberances. The horizontal lines 164, 164' respectively intersect the outer edge of the radiator at intersection points 166, 166'. The portion of the horizontal line extending from the member local minimum 160 to the intersection point 166 replaces the current portion of the outer edge extending between the member local minimum 160 and intersection point 166. Likewise, the portion of the horizontal line extending from the member local minimum 160' to the intersection point 166' replaces the current portion of the outer edge extending between the member local minimum 160' and intersection point 166'. This alteration of the outer edge facilitates a determination of whether the wide-narrow-wide and dimensional characteristics are present in the radiator 150. With reference to FIG. 8C, a width profile 170 for the radiator 150 with the modified outer edge is shown. The width profile 170 has an indefinite profile local minimum in area 172 and profile local maximums 174, 176. The width profile 170 satisfies the wide-narrow-wide characteristics and the vertical characteristic. As can be appreciated from FIGS. 7A-7C, the width profile 170 can be modified by filtering to facilitate the determination of whether the horizontal dimensional characteristic is present.

There is another group of symmetric planar radiators with shapes that, when combined with the other element(s) needed to form a monopole or dipole antenna, result in an antenna with the noted performance but render assessment of whether the radiator shape satisfies the wide-narrow-wide characteristic problematic. The feature common to this group of symmetric radiator shapes is two or more upwardly (away from the pseudo-ground plane) extending protuberances. Charac-

teristic of such protuberances is that a horizontal line (i.e., a line parallel to the pseudo-ground plane) can be drawn that passes through a first portion of the radiator, a second portion of the radiator, and a gap between the first and second portions of the radiator. Further, there is a member inflection point on the outer edge that is located below the horizontal line and on the portion of the outer edge that is between the two points at which the horizontal line intersects the outer edge to span the gap. In this case, the member inflection point has zero slope, space above and immediately adjacent to the inflection point, a portion of the radiator located below the inflection point, and the outer edge extends upwardly (away from the pseudo-ground plane) on both sides of the inflection point. Further, there is a member local maximum associated with each protuberance. A member local maximum is characterized by a zero slope and space immediately adjacent to and above the local maximum. Further, the portion of the edge to one side of the member local maximum has a positive slope and the portion of the edge to the other side of the member local maximum has a negative slope.

The problem in assessing the wide-narrow-wide characteristic in symmetric planar radiators that have upwardly extending protuberances is addressed by splitting the radiator into two or more radiator elements and analyzing the elements to determine if one of the two or more elements satisfies the wide-narrow-wide and dimensional characteristics. The splitting into elements is achieved by horizontal shading, which can be conceptualized as drawing horizontal lines beginning at a member local maximum and proceeding towards the pseudo-contact point with no gaps in any of the horizontal lines. A width profile is then produced for each of the elements (one element is associated with each member local maximum) and analyzed to determine if the wide-narrow-wide and dimensional characteristics are satisfied. If one element satisfies the wide-narrow-wide and dimensional characteristics, the symmetrical planar radiator is sufficient to realize the noted operational performance.

With reference to FIGS. 9A-9G, an example of a symmetric planar radiator with three upwardly extending protuberances, radiator 180, is discussed. The planar radiator 180 is positioned relative to a pseudo-ground plane 182 and a normal plane 184 so as to be able to assess whether the radiator 180 is symmetric. In this regard, a pseudo-contact portion 186 of the radiator 180 is positioned to contact the pseudo-ground plane 182. As can be appreciated, the radiator 180 is bilaterally symmetric relative to the normal plane 184 and, hence, considered to have the symmetric characteristic. A horizontal line 188 can be drawn through the radiator 180 such that the horizontal line passes through first, second, and third portions of the radiator and a gap 190 between the first and second portions and a second gap 190' between the second and third portions. Further, there is a member inflection point 192 located on the portion of the outer edge that is between the points at which the horizontal line 188 intersects the outer edge in spanning the gap 190. There is a second member inflection point 192' located on the portion of the outer edge that is between the points at which the horizontal line 188 intersects the outer edge in spanning the gap 190'. As such, the radiator 180 has at least two upwardly extending protuberances and, in this case, three upwardly extending protuberances. Further, the radiator 180 has three member local maximums, namely, a first member local maximum 194, a second member local maximum 196, and a third member local maximum 197. With reference to FIG. 9B, a first radiator element 198 is identified by horizontal shading commencing at the first member local maximum 194 and proceeding to the pseudo-contact portion 186. With reference to FIG. 9C, a

second radiator element 200 is identified by horizontal shading commencing at the second member local maximum 197 and proceeding to the pseudo-contact portion 186. With reference to FIG. 9D, a third radiator element 198' is identified by horizontal shading commencing at the third member local maximum 196 and proceeding to the pseudo-contact portion 186. With reference to FIG. 9E, the first radiator element 198 has a width profile 204 that has an indeterminate profile local minimum 206, a profile local maximum in 208 (due to a right angle corner in the outer edge), and a profile local maximum 210. The width profile 204 satisfies the wide-narrow-wide characteristic due to the local minimum 206 being located between two local maximums. Further, the vertical distance between the profile local minimum 206 and the indeterminate profile maximum 208 can be determined. However, it appears that the horizontally closer profile local maximum to the profile local minimum 206 will be the profile local maximum 210. To determine this "indeterminate" profile local maximum, the profile 204 can be filtered, an example of which was discussed with respect to FIGS. 5A-5C. With reference to FIG. 9F, the second radiator element 200 has a width profile 214. The width profile 214 does not satisfy the wide-narrow-wide characteristic. With reference to FIG. 9G, the third radiator element 198' has a width profile 204' that is, due to the symmetry of the radiator, substantially identical to the width profile 204. In this regard, the width profile 204' has a profile local minimum 206', an indeterminate profile local maximum in area 208', and a profile local maximum 210'. The width profile 204', as with width profile 204, satisfies the wide-narrow-wide characteristic and vertical distance characteristic. Whether the horizontal distance characteristic is satisfied can be determined, as noted with respect to profile 204, by filtering.

There is a group of symmetric planar radiators with shapes that, when combined with the other element(s) needed to form a monopole or dipole antenna, result in an antenna with the noted performance but render assessment of whether the radiator shape satisfies the wide-narrow-wide characteristic and/or dimensional characteristics problematic. Characteristic of this group of radiators is that the outer edge of the radiator has one or more features that require two or more: (a) filtering due to the presence of one or more high frequency features, (b) redefinition of the outer edge due to the presence of one or more downwardly extending protuberances; and (c) splitting into two or more radiation elements due to the presence of two or more upwardly extending protuberances. The possible combinations are: (1) a shape with two or more downwardly extending protuberances and one or more high frequency features, (2) a shape with two or more upwardly extending protuberances and one or more high frequency features (3) a shape with two or more upwardly extending protuberances and two or more downwardly extending protuberances, and (4) a shape with two or more upwardly extending protuberances, two or more downwardly extending protuberances, and one or more high frequency features. Generally, any such outer edge shape can be analyzed to produce an assessment width profile by: (a) first, redefining the outer edge to address any downwardly extending protuberances, (b) second, identifying any radiation elements attributable to two or more upwardly extending protuberances, and (c) third, filtering the width profile for the redefined outer edge resulting from step (a) (there were no radiation elements identified) to remove high frequency effects or filtering the width profile for one or more of the radiation elements identified in step (b) (there may or may not have been any downwardly extending protuberances) to remove high frequency effects. In this regard, to facilitate the descrip-

tions of features that relate to the performance characteristics and the features of the radiator that require some kind of modification to facilitate the assessment of whether the radiator possesses the features that provide the operational performance, the exemplary outer edge shapes discussed thus far have been relatively simple. It should, however, be appreciated that very complex shapes may also provide the noted operational performance and require numerous modifications of the outer edge or a width profile to produce an assessment width profile that can be used to determine whether the shape is sufficient to realize the noted operational performance.

With reference to FIG. 10, an example of a relatively complex symmetric planar radiator 220 is described. The radiator 220 is positioned relative to a pseudo-ground plane 222 and a normal plane 224 so as to be able to assess whether the radiator 220 is symmetric. In this regard, a pseudo-contact portion 238 comprised of points 228A, 228B, which are separated from one another, is positioned to contact the pseudo-ground plane 222. As can be appreciated, the radiator 220 is bilaterally symmetric relative to the normal plane 224 and, hence, considered to have the symmetric characteristic. Further, the radiator 220 has member local minimums 230, 230', 232, and 232'. Further, points 228A, 228B are each member local minimums. A horizontal line 234 crosses four gaps, one on each side of the member local minimum 230 and one on each side of member local minimum 230'. The horizontal line 234 would redefine the outer edge of the radiator but for the presence of the member local minimums 232, 232'. To elaborate, a horizontal line 236 extending between the member local minimums 232, 232' is closer to the pseudo-ground plane 222 and supersedes the horizontal line 234. A horizontal line 238 extends between the points 228A, 228B and redefines that portion of the outer edge of the radiator 220. Moreover, the horizontal line 238 redefines the pseudo-contact portion of the outer edge. The normal plane 224 passes through the mid-point of the horizontal line 238. The outer edge of the radiator 220 also has three member local maximums 240, 242, and 243. As such, there will be three radiator elements associated with the radiator. The radiator element associated with the member local maximum 240 will have a width profile with high frequency components due to the presence of the "teeth" structure 244. Consequently, the width profile associated with that element will likely need to be modified by filtering to assess whether the element satisfies the wide-narrow-wide characteristic and the dimensional characteristics. The width profile for the radiator element associated with the member local maximum 242 is substantially identical (due to symmetry) to the width profile associated with element 240. As such, if the width profile for the element associated with member local maximum 240 has the wide-narrow-wide and dimensional characteristics, the width profile for the element associated with the member local maximum 242 will also have these characteristics. The width profile for the element associated with the member local maximum 243 will also satisfy the wide-narrow-wide characteristic. Further, it appears that the width profile associated with at least one and potentially all of the three radiator elements will satisfy the wide-narrow-wide test. Whether the dimensional characteristics are present will require careful analysis of the width profile and be dependent upon the value of λ_{low} .

Thus far, the exemplary symmetric planar radiators that have been described have been assessed with respect to features associated with the outer edge of the radiator. None of the exemplary radiators had an inner edge that defined a void. With respect to outer edge assessments, any gap defined by the radiator is treated as if the gap was "filled in" or not

present. It should, however, be appreciated that a symmetric planar radiator can be symmetric due to the presence of symmetric outer edge and a symmetric inner edge that defines a void. Further, many such symmetric planar radiators are capable of operating to facilitate the noted performance. With reference to FIG. 11, an example of a symmetric planar radiator with a symmetric outer edge 258 and a symmetric inner edge 260 that defines a void (radiator 250) is discussed. The radiator 250 is positioned relative to a pseudo-ground plane 252 and a normal plane 254 so as to be able to assess whether the radiator 250 is symmetric. In this regard, a pseudo-contact portion 256 is positioned to contact the pseudo-ground plane 252. As can be appreciated, the radiator 250 is bilaterally symmetric relative to the normal plane 254. Assessment of whether a radiator has satisfies the wide-narrow-wide characteristic when the focus is on one or more voids, proceeds in a similar but somewhat different fashion than with the outer edge assessment. To elaborate, the assessment of whether symmetric radiator with a symmetric outer edge and symmetric inner edge that defines a void is sufficient for realizing the noted performance is done by producing a width profile in which the presence of the void is not ignored. In this case, the width at a vertical location at which a horizontal line passes through the void is the sum of the "sub-widths" of the portions of the radiator present on each side of the void. The width profile is assessed to determine whether the noted wide-narrow-wide and dimensional characteristics are present.

FIG. 12 illustrates an example of a monopole antenna 270 comprised of a ground plane 272 and a symmetric planar radiator 274 that is disposed substantially perpendicular to but separated from ground plane 272. In operation, the monopole antenna 270 operates, substantially as a consequence of the symmetric planar radiator 274, to have the noted performance characteristics of: (a) at least a 3:1 bandwidth, (b) a VSWR of less than about 3:1 over the bandwidth, (c) vertical polarization, and (d) a relatively constant gain perpendicular or broad-side to the plane of the radiator.

FIG. 13 illustrates an example of a dipole antenna 280 comprised of first and second symmetric planar radiators 280A, 280B, which are substantially coplanar. The radiators 280A, 280B are positioned with respect to one another in a "mirrored" relationship. In operation, the dipole antenna 280 operates, substantially as a consequence of the symmetric planar radiators 280A, 280B, to have the noted performance characteristics of: (a) at least a 3:1 bandwidth, (b) a VSWR of less than about 3:1 over the bandwidth, (c) vertical polarization, and (d) a relatively constant gain perpendicular or broad-side to the plane of the radiator.

With reference to FIGS. 14A and 14B, a reference symmetric planar radiator 290A and an improved symmetric planar radiator 290B as described herein are discussed. The radiator 290A is positioned perpendicular to a pseudo-ground plane 292A and a normal plane 294A. From this positioning, it can be seen that radiator 290A is symmetrical. The radiator 290B is positioned perpendicular to a pseudo-ground plane 292B and a normal plane 294B. From this positioning, it can be seen that radiator 290B is also symmetrical. However, radiator 290A does not meet the wide-narrow-wide characteristic. In contrast, radiator 290B does meet the wide-narrow-wide characteristic and also meets the dimensional characteristics.

In FIG. 15A, it can be seen that both radiators 290A and 290B show a VSWR of less than 3:1 over the operating frequency band, which is also greater than 3:1. In this case, the operating frequency band extends approximately from 1.0 GHz to about 5.0 GHz. With respect to FIG. 15B, the swept gain at the point perpendicular to the plane of the radiators

19

290A, 290B is shown. The radiator 290A shows a significant gain drop-out at approximately 3.5 GHz. In contrast, radiator 290B shows a substantially constant gain over the entire frequency band, thereby avoiding the gain drop-out experienced with radiator 290A. With reference to FIGS. 16A-16L, the elevation pattern in the plane perpendicular to the planes of radiators 290A, 290B are shown at various frequencies in the operating frequency band. The elevation patterns for the reference radiator 290A are identified with dashed lines. The elevation patterns for the improved radiator 290B are identified with solid lines. From FIG. 16H, the drop-out in gain at $\pm 90^\circ$ angles is apparent for the reference radiator 290A. In contrast, the improved radiator 290B does not show any such drop-out in gain. FIGS. 16I-16L, illustrate that the reference radiator 290A never achieves the gain of the improved radiator 290B at the same $\pm 90^\circ$ angles.

The foregoing description of the invention is intended to explain the best mode known of practicing the invention and to enable others skilled in the art to utilize the invention in various embodiments and with the various modifications required by their particular applications or uses of the invention.

What is claimed is:

1. A radiator structure, having, when used operatively, a relatively stable impedance and radiation pattern over a wide bandwidth comprising:

- a planar radiator that has an outer edge;
- the outer edge having a pseudo-contact portion;
- wherein, when the planar radiator is positioned:
- (a) perpendicular to a pseudo-ground plane;
- (b) perpendicular to a normal plane that is perpendicular to the pseudo-ground plane;
- (c) such that only the pseudo-contact portion contacts the pseudo-ground plane;
- (d) such that the normal plane intersects a midpoint of the pseudo-contact portion of the planar radiator;
- (e) such that the planar radiator, other than the pseudo-contact portion of the planar radiator, is entirely located to one side of the pseudo-ground plane; and
- (f) such that the planar radiator is oriented relative to the pseudo-ground plane as the planar radiator would be oriented, if used in a monopole antenna, relative to an idealized infinite ground plane;

the planar radiator is bilaterally symmetric relative to the normal plane; and

wherein, when the planar radiator is in operation in one of a monopole antenna and dipole antenna, the antenna:

- (a) operates over a bandwidth in which the ratio of the highest frequency (f_{high}) in the bandwidth to the lowest frequency (f_{low}) in the bandwidth is at least 3:1;
- (b) has a continuous VSWR of less than about 3:1 over the bandwidth;
- (c) is vertically polarized; and

has a relatively constant gain perpendicular to the plane of the radiator;

wherein the planar radiator has an assessment width profile that extends from a member local maximum to the pseudo-contact portion;

wherein the assessment width profile has a profile local minimum located between a first profile local maximum and a second profile local maximum;

wherein the first profile local maximum is located in a space extending from the profile local minimum to and including the member local maximum;

wherein the second profile local maximum is located in a space extending from the profile local minimum to and including the pseudo-contact portion;

20

wherein no other profile local maximum is located between the profile local minimum and either the first profile local maximum or second profile local maximum;

wherein a profile local minimum has a zero slope;

wherein each of the first and second profile local maximums has a zero slope;

wherein the first profile local maximum,

if occurring at a member local maximum, is followed by a negative slope; and

if occurring between the member local maximum and the profile local minimum is preceded by a positive slope and followed by a negative slope;

wherein the second profile local maximum,

if occurring at the pseudo-contact portion, is preceded by a positive slope;

if occurring between the profile local minimum and the pseudo-contact portion is preceded by a positive slope and followed by a negative slope;

wherein the vertical distance between the profile local minimum and the vertically nearer of the first and second profile local maximums is at least 0.02 times the wavelength associated with f_{low} ($0.02\lambda_{low}$); and

wherein the horizontal distance between the profile local minimum and the horizontally nearer of the first and second profile local maximums is at least $0.01\lambda_{low}$.

2. A radiator structure, as claimed in claim 1, wherein: the assessment width profile is an unprocessed width profile for the planar radiator.

3. A radiator structure, as claimed in claim 1, wherein: the assessment width profile is a processed width profile for the planar radiator that has been filtered so as to pass substantially only a first harmonic of the unprocessed width profile.

4. A radiator structure, as claimed in claim 1, wherein: the assessment width profile is a width profile for a redefined outer edge of the planar radiator;

the outer edge being redefined if (a) a horizontal line passing through the planar radiator passes through a gap, the gap not being caused by a void in the planar radiator, and there is a member local inflection point in the planar radiator above the portion of the horizontal line that passes through the gap and (b) there is at least one member local minimum in the planar radiator located between a member local maximum of the planar radiator and the pseudo-contact portion;

the outer edge being redefined such that each horizontal line extending from a member local minimum in the planar radiator and intersecting the outer edge so as to define a closed area that was previously an open area adjacent to the member local minimum becomes a portion of a redefined outer edge.

5. A radiator structure, as claimed in claim 1, wherein: the planar radiator has an assessment width profile that is a filtered width profile for a redefined outer edge of the planar radiator;

the outer edge being redefined if (a) a horizontal line passing through the planar radiator passes through a gap, the gap not being caused by a void in the planar radiator, and there is a local maximum in the planar radiator above the portion of the horizontal line that passes through the gap and (b) there is at least one member local minimum in the planar radiator located between a member local maximum of the planar radiator and the pseudo-contact portion;

the outer edge being redefined such that each horizontal line extending from a member local minimum in the planar radiator and intersecting the outer edge so as to

21

define a closed area that was previously an open area immediately adjacent to the member local minimum becomes a portion of a redefined outer edge;

the redefined outer edge having a redefined width profile; the assessment width profile is a redefined width profile 5 that has been low-pass filtered so as to pass substantially only a first harmonic of the redefined width profile.

6. A radiator structure, as claimed in claim 1, wherein: the planar radiator has multiple assessment width profiles; the multiple assessment width profiles resulting if (a) a 10

horizontal line passing through the planar radiator passes through a gap, the gap not being caused by a void in the planar radiator, and there is a member inflection point below the portion of the horizontal line that passes through the gap, (b) multiple elements are defined by horizontal shading starting at each member local maximum and extending to the pseudo-contact portion, and (c) each of the multiple elements has an assessment 15 width profile that is a width profile for the element.

7. A radiator structure, as claimed in claim 1, wherein: the planar radiator has multiple assessment width profiles; the planar radiator has a redefined outer edge the outer edge 20

being redefined if (a) a horizontal line passing through the planar radiator passes through a gap, the gap not being caused by a void in the planar radiator, and there is a member local inflection point in the planar radiator above the portion of the horizontal line that passes through the gap and (b) there is at least one member local minimum in the planar radiator located between a member local maximum of the planar radiator and the pseudo-contact portion;

the outer edge being redefined such that each horizontal line extending from a member local minimum in the planar radiator and intersecting the outer edge so as to define a closed area that was previously an open area adjacent to the member local minimum becomes a portion of a redefined outer edge;

the multiple assessment width profiles resulting if (a) a horizontal line passing through the planar radiator passes through a gap, the gap not being caused by a void in the planar radiator, and there is a member local minimum below the portion of the horizontal line that passes through the gap, (b) multiple elements are defined by horizontal shading starting at each member local maximum and extending to the pseudo-contact portion, and (c) each of the multiple elements has an assessment 35 width profile that is a width profile for the element; the multiple assessment width profiles are the width profiles for each of the multiple elements.

8. A radiator structure, as claimed in claim 1, wherein: the planar radiator has multiple assessment width profiles; the planar radiator has a redefined outer edge the outer edge 40

being redefined if (a) a horizontal line passing through the planar radiator passes through a gap, the gap not being caused by a void in the planar radiator, and there is a member local inflection point in the planar radiator above the portion of the horizontal line that passes through the gap and (b) there is at least one member local minimum in the planar radiator located between a member local maximum of the planar radiator and the 45 pseudo-contact portion;

22

the outer edge being redefined such that each horizontal line extending from a member local minimum in the planar radiator and intersecting the outer edge so as to define a closed area that was previously an open area adjacent to the member local minimum becomes a portion of a redefined outer edge;

the planar radiator with a redefined outer edge has multiple elements, each with an element width profile, the multiple assessment width profiles resulting if (a) a horizontal line passing through the planar radiator passes through a gap, the gap not being caused by a void in the planar radiator, and there is a member inflection point below the portion of the horizontal line that passes through the gap, (b) multiple elements are defined by horizontal shading starting at each member local maximum and extending to the pseudo-contact portion, and (c) each of the multiple elements has an assessment width profile that is a width profile for the element; at least one of the multiple elements has a filtered element width profile that has been processed so as to pass substantially only a first harmonic of the element width profile;

the multiple assessment width profiles includes each filtered element width profile and element width profile.

9. A radiator structure, as claimed in claim 1, wherein: the planar radiator has multiple assessment width profiles; the planar radiator has multiple elements, each with an 25

element width profile, the multiple assessment width profiles resulting if (a) a horizontal line passing through the planar radiator passes through a gap, the gap not being caused by a void in the planar radiator, and there is a member inflection point below the portion of the horizontal line that passes through the gap, (b) multiple elements are defined by horizontal shading starting at each member local maximum and extending to the pseudo-contact portion, and (c) each of the multiple elements has an assessment width profile that is a width profile for the element;

at least one of the multiple elements has a filtered element width profile that has been processed so as to pass substantially only a first harmonic of the element width profile;

the multiple assessment width profiles includes each filtered element width profile and element width profile.

10. A radiator structure, as claimed in claim 1, further comprising:

a ground plane, which is not the pseudo-ground plane, located adjacent to but separated from the planar radiator;

wherein the planar radiator and ground plane substantially form a monopole antenna.

11. A radiator structure, as claimed in claim 1, further comprising:

a second planar radiator located adjacent to but separated from the planar radiator;

wherein the planar radiator and second planar substantially form a dipole antenna.

12. A radiator, as claimed in claim 11, wherein: the second planar radiator is a mirror-image of the planar radiator.
